WITNESSED:

UNITED STATES PATENT OFFICE.

JACOB W. SHOOK, OF MILTON, PENNSYLVANIA.

WRENCH.

1,413,495.

Specification of Letters Patent. Patented Apr. 18, 1922.

Application filed May 27, 1921. Serial No. 473,111.

To all whom it may concern:

Be it known that I, JACOB W. SHOOK, a citizen of the United States, residing at Milton, in the county of Northumberland and 5 State of Pennsylvania, have invented new and useful Improvements in Wrenches, of which the following is a specification.

My present invention has reference to improvements in wrenches.

10 My object is to produce a wrench in which the handle is provided with a hollow head through which is guided a jaw provided with a toothed shank that is engaged by a worm, while also received in the head is the 15 shank of a second jaw firmly supported by contacting engagement with certain of the walls provided in the slot and having means engaged by the shank of the first mentioned jaw, whereby, when the first mentioned jaw 20 is moved longitudinally, the second mentioned jaw will be moved at a less rate of speed right angularly with respect to the first mentioned jaw, so that the handle may be held at a determined angle with respect 25 to the object to be engaged between the jaws, and the said jaws properly guided by contacting engagement with the support for the object to engaging position with said object and the necessity of tilting or otherwise manipulating the handle of the wrench 30 for causing a proper engagement of the jaws with the object will be entirely overcome.

A still further object is to produce a 35 wrench in which two movable jaws are employed, coengaging means being provided between the jaws, whereby one jaw is caused to move angularly with respect to the other jaw and whereby the engaging faces of the 40 jaws are at all times retained parallel.

It is a still further object to produce a 45 wrench provided with movable jaws which are so constructed and arranged as to be reinforced to a degree which will render the same as strong and effective as a wrench that has rigid jaws.

The foregoing, and other objects which 50 will appear as the nature of the invention is better understood, may be accomplished by a construction, combination and operative association of parts, such as is disclosed by the drawings which accompany and which form part of this specification.

In the drawings:—

55 Figure 1 is an elevation of a wrench in accordance with this invention.

Figure 2 is a similar view with the side plate of the head removed.

Figure 3 is a sectional view on the line 3—3 of Figure 1. 60

Figure 4 is a sectional view on the line 4—4 of Figure 1.

Figure 5 is a side elevation of the head with the side plate removed, and the jaws and operating worm being likewise removed. 65

Figure 6 is an edge view of the same.

Figure 7 is a perspective view of the jaw provided with the toothed shank.

Figure 8 is a similar view of the second jaw. 70

Referring now to the drawings in detail, the numeral 1 designates the handle of the wrench which is formed at one end with an enlargement that provides the same with what I will term a head and which is designated by the numeral 2. The outer wall of the head 2 is arranged angularly with respect to the handle, and is, for a determined length depressed to provide a pocket 3. The pocket enters from the end and the outer face of the head, and provides the said head with two right angular walls 4 and 5 respectively. The head is further provided with a slot 6 the inner wall of which being in a line with the wall 4 of 80 the pocket. Entering the pocket 3, from the rear angle end 7 of the head 2 is a slot 8, while below the slot, and communicating with the inner wall thereof, the head has a transverse opening 9 therethrough. The 90 opening 9 is designed to receive therein a worm screw 10, the shaft therefor being indicated by the numeral 11, and being in the nature of a pin that has its outer end enlarged, and threaded as at 12 to engage 95 threads 13 in the widened end of the slot through which the pin passes. The threaded end of the pin is also kerfed, as at 14, whereby the same may be removed.

As two movable jaws are employed, I 100 will, for the sake of convenience, refer to one as the outer jaw, and the other as the inner jaw. The outer jaw is indicated by the numeral 15 and is provided with a right angular shank 16. The shank has a toothed 105 edge 17 which is engaged by the worm screw 10. The shank is of a thickness approximately equaling one-half of the thickness of the jaw 15, one of the side walls of the said shank being flush with one of the sides 110 of the jaw, and its opposite side is provided with an angularly arranged groove 18.

The inner jaw is indicated by the numeral 19 and is also provided with a depending portion forming a shank 20. The shank, for the major portion of its length is of a 5 width approximately equaling one-half of the thickness of the jaw 19, one of the sides of the shank being flush with one of the sides of the jaw and its second side is provided with an angularly disposed tongue 21 10 that is designed to be received in the angle groove 18 in the shank 16 of the jaw 15. The shank 20 of the jaw 19 has the side thereof flush with the side of the jaw reduced, as at 22, the said reduced portion 15 being received in the slot 6, and the shoulder 23 provided at the inner end of the said reduced portion being designed to rest on the shoulder 24 formed at the inner end of the slot 6, the said shoulder 24 being disposed a slight distance below the wall 5 of 20 the pocket 3. The inner straight edge of the shank 20, and a portion of the head of the jaw 19 is designed for contacting engagement with the wall 4 of the pocket 3, and whereby the jaw 19 is effectively braced.

The shanks of the jaws are enclosed in the head by a removable plate 25. The straight side of the shank 20 is in contacting engagement with the inner side wall of the 30 pocket, and as stated, the reduced portion 22 of the said shank which is received in the slot 6, contacts with both the end and side walls of the said slot. The shanks of the jaws are enclosed in the pocket by a removable plate 26, and this plate contacting with the outer straight face of the jaw 15 and its shank 16 holds the straight side of the jaw in contacting engagement with the inner wall of the pocket 3, and also causes the 40 reduced face of the shank to properly engage with the reduced face of the shank 20 of the jaw 19.

The turning of the screw will move the shank 16 longitudinally through the pocket, 45 bringing the jaw 15 toward or away from the jaw 19. The movement of the jaw 15, incident to the tongue and groove engagement between the shanks of the respective jaws, will also cause the jaw 19 to travel 50 angularly with respect to the travel of the jaw 15, and as a consequence the handle may be arranged at a determined angle when the jaws rest on a surface to the opposite sides of a nut or other article to be engaged, so that it is not necessary for the operator to manipulate the handle to bring the jaws to a proper position for engagement with the article.

It is believed that the foregoing description, when taken in connection with the

drawings will fully set forth the construction and advantages of the improvement, but it is to be understood that the description and illustration refer only to a satisfactory embodiment of the invention as it 65 now appears to me and that I am entitled to all such changes therefrom as fall within the scope of what is claimed.

Having described the invention, I claim:—

1. In a wrench, a handle having a head, 70 jaws having angle shanks arranged inlapping relation and movable in the head, an element on one of the shanks, means on the other shank receiving said element, means carried by the head and engaging the last 75 mentioned shank for imparting a longitudinal movement thereto, and by virtue of such movement to cause the element on the first mentioned shank to travel in the means on the last mentioned shank for moving the 80 first mentioned shank.

2. In a wrench, a handle having a slotted head, a jaw having an angularly toothed shank arranged in the head, a worm screw revoluble in the head and in engagement 85 with the teeth of the shank, a second jaw having a shank arranged right angularly with respect to the shank of the first mentioned jaw, and coengaging means between the shanks of the respective jaws whereby 90 the last mentioned jaw is moved right angularly with respect to the first mentioned jaw when the said first mentioned jaw is moved by the operation of the worm screw.

3. In a wrench, a handle having an angle 95 head at one end thereof which is provided with a pocket that opens at its end and at its outer edge, said head having right angular slots which communicate with the pocket at the rear thereof, and the inner wall of 100 both of the slots providing shoulders, said head having a transverse opening therethrough which communicates with the longitudinal slot, a worm screw journaled in said opening, a jaw having an integral right 105 angular shank of a less thickness than that of the jaw, said shank having an angle slot on the inner reduced face thereof and having teeth which are engaged by the worm screw, a second jaw having a reduced shank 110 which rests against the inner wall of the pocket and which has a reduced extension received in the second mentioned slot, and the shank of the second mentioned jaw having an angle tongue which is received in 115 the angle slot of the shank of the first mentioned jaw, all as and for the purpose set forth.

In testimony whereof I affix my signature.

JACOB W. SHOOK.
